UNITED STATES PATENT OFFICE

119,877

DESIGN FOR A GLIDER OR SIMILAR
ARTICLE

Jacob C. Feldman, Boston, Mass., assignor to
New England Bedding Company, Medford,
Mass., a corporation of Massachusetts

Application August 17, 1939, Serial No. 86,742

Term of patent 14 years

To all whom it may concern:

Be it known that I, Jacob C. Feldman, a citizen of the United States of America, residing at Boston, in the county of Suffolk and Commonwealth of Massachusetts, have invented a new, original, and ornamental Design for a Glider or Similar Article, of which the following is a specification, reference being had to the accompanying drawing, forming a part thereof.

Fig. 1 is a perspective view of the glider, showing my new design;

Figs. 2 and 3 are top plan and end elevational views, respectively, of the glider; and

Fig. 4 is a front elevational view of one end of the glider.

The characteristic features of my design reside in the parts shown in the solid lines, the end panels being rigid and the front panel constituting a valance of flexible material joined to and being of the same flexible material as the covering of the seat cushion.

I claim:

The ornamental design for a glider or similar article, substantially as shown and described.

JACOB C. FELDMAN.
